DESIGN FOR AN ARTICLE-DISPENSING MACHINE

Herbert Steiglitz, Brooklyn, N. Y., assignor to Peerless Weighing & Vending Machine Corporation, Long Island City, N. Y., a corporation of Delaware

Application July 10, 1937, Serial No. 70,360

Term of patent 14 years

To all whom it may concern:

Be it known that I, Herbert Steiglitz, a citizen of the United States, residing at Brooklyn, county of Kings, and State of New York, have invented a new, original, and ornamental Design for an Article-Dispensing Machine, of which the following is a specification: reference being had to the accompanying drawing, forming a part thereof.

The figure is a front perspective view of an article-dispensing machine embodying my design.

I claim:

The ornamental design for an article-dispensing machine, substantially as shown.
